ABSTRACT: A ganged tufting needle unit having a multiplicity of parallel needles formed integral with a common holder which includes a pair of reference surfaces and is adopted to be accurately attached as a unit to a needle bar of a tufting machine. The holder is divided into standardized sections by score lines at predetermined needle intervals along its length so that if one or more needles should break the section including the broken needles can be separated from the remainder of the unit and a standard replacement unit may be readily substituted therefor. Also disclosed is a latch needle unit and a yarn guide unit having the same features as the tufting needle unit. A method for manufacturing the different units from a metal strip comprising a series of die pressing, punching and grinding steps is described.

MULTINEEDLE UNIT

BACKGROUND OF THE INVENTION

This invention relates to yarn-handling instrumentalities and more particularly to a ganged unit having a plurality of yarn-handling fingers unitary with a common support for use in tufting or knitting machines.

Carpets and similar tufted articles are manufactured by pushing yarn through a backing material to produce loops on one side thereof. Machines that perform this process are known in the art as tufting machines and comprise a transversely extending needle bar carrying a multiplicity of needles which carry the yarn and pierce the backing fabric, a needle plate supporting a longitudinally moving backing fabric and having a multiplicity of holes through which the needles pass after piercing the fabric, and a multiplicity of loopers generally located below the needle plate for engaging the yarn carried by respective needles after the latter have passed through the backing fabric and the needle plate. A machine of this general type is illustrated in U.S. Pat. No. 3,108,553.

The requirement of good loop formation mandates that each yarn-carrying needle must properly cooperate with its corresponding looper. The needle eye and the yarn groove in the needle must be properly positioned relative to the looper so that the loop formed will be available to the looper. Furthermore, the needle must pass close enough to the looper so that the latter may pick up a loop, but it should not pass so close to the looper that contact would occur resulting in damage to the needle or looper. The position of the needle relative to the looper thus being critical, it has been the practice to incorporate in such machines a needle bar having a multiplicity of extremely accurately bored needle-receiving holes. Each needle must then individually be fitted, adjusted and fastened in the needle bar relative to the looper. An illustration of a needle bar of such construction can be found in U.S. Pat. No. 3,398,708.

Inasmuch as tufting machines may contain as many as 3,000 needles, the needle bar must be accurately bored to accommodate this sum. This, of course, can be a very costly procedure. Furthermore, since each needle must be individually inserted into a bore and adjusted and fastened therein, it becomes a costly, tedious and time-consuming process to set up a tufting machine for proper operation and to later replace needles broken during the subsequent tufting operation.

Similar problems are involved in the knitting art and especially in the warp knitters of the Raschel and tricot types. These machines use a plurality of needles and yarn guides which must be accurately positioned in the machine. Misaligned needles or guides result in the production of faulty fabric.

The yarn guides are bladelike devices having a hole in one end lightweight which are used in Raschel and tricot machines to guide the feeding of yarn to the needles. The guides in these machines, in order to properly align them relative to each other, are set in guide leads, i.e., cast in leaded units, which are in turn bolted to a guide bar. This is also true of the needles in these machines. The guides and needles that are so embedded in lead must be properly anchored therein to prevent extraction during the knitting operation. This requires that some type of anchoring aid, such as a notch, must be formed in the shanks, thus adding to the complexity and cost of the unit. A further deficiency of the present systems is that the heavy mass of lead into which the needles and guides are cast provide an obstacle to the attainment of high-speed operation. An approach to the reduction of the large mass resulted in mounting the needles directly in the respective bars, but this was found to be inadequate for the same reasons stated in regard to tufting.

SUMMARY OF THE INVENTION

Applicant's invention overcomes these difficulties of the prior tufting and knitting arts by providing a unit having a mul-

tiplicity of similar yarn-handling instrumentalities of one-piece construction that together with like units may be quickly and accurately fastened in the machine. In one embodiment of the invention, there is provided a multineedle unit of the tufting type which is adopted to be applied to a less expensive needle bar of a tufting machine. In another embodiment there is provided a multineedle unit of the latch type for a Raschel knitting machine. A third embodiment provides a multiyarn guide unit which is adopted to be used in a warp knitting machine. In each embodiment of the invention there is provided a comblike structure having a multiplicity of spaced fingerlike elements integral with and extending from a common shank. Each fingerlike element has a free end which is shaped to engage and control a strand of yarn. In the various embodiments the fingerlike element may be a tufting needle, a latch needle or a yarn guide. Each of the units may be economically manufactured by a process comprising a series of punching, stamping and twisting steps to form each fingerlike element simultaneously.

It is therefore the primary object of this invention to provide an inexpensive unitary comblike structure comprising a multiplicity of yarn-handling instrumentalities which can as a unit be quickly and accurately fastened to a yarn-utilizing machine.

A further object of this invention is to provide a multineedle unit adapted for use in a tufting machine which obviates the need for a needle bar having a multiplicity of accurately machined needle bores.

A still further object of this invention is the provision of a multineedle unit of the latch type adapted for use in a warp knitting machine which unit is light in weight so as not to present an obstacle to high-speed operation.

A yet still further object of this invention is to provide a light-weight multiyarn guide unit adapted for use in a knitting machine.

The inevitable needle breakages that occur during tufting and knitting operations are provided for and economically dealt with by the present invention by scoring the units at predetermined intervals along the length thereof and providing standard ready replacement units. When a breakage occurs, the subunit containing the broken instrumentality or instrumentalities may be separated along the score lines from the remainder of the unit and a replacement subunit readily substituted therefor with a minimum of downtime.

It is, therefore, a still further object of the present invention to provide a quick, economical and easy replacement of yarn-handling instrumentalities broken during the tufting and knitting operation.

BRIEF DESCRIPTION OF THE DRAWINGS

For a fuller understanding of the nature and objects of the invention reference should be had to the following description taken in connection with the accompanying drawings, in which:

FIG. 1 is a fragmentary perspective view of tufting needle units of the present invention fastened to a needle bar shown broken away, with one needle shown in cross section;

FIG. 2 is an elevational end view of one tufting needle unit of FIG. 1 as viewed from the right end of FIG. 1;

FIG. 3 is an elevational end view of one tufting needle unit of FIG. 1 as viewed from the left end of FIG. 1;

FIG. 4 is a fragmentary front elevational view of a tufting needle unit being formed showing the result of the step of forming fingers in a strip of metal;

FIG. 5 is a view similar to FIG. 4 showing the needle fingers after die-pressing the fingers to form the eye, the yarn groove and the scarf, and to contour the tip of the needle fingers;

FIG. 6 is a view similar to FIG. 5 after punching or stamping the metal displaced during die-pressing;

FIG. 7 is a cross sectional view along line 7—7 of FIG. 6, but after the eye of the needle has been rounded by punching;

FIG. 8 is an end view of the unit after the first point grinding step looking at the unit from the left end of FIG. 6;

FIG. 9 is a fragmentary view of a typical latch needle showing its component parts;

FIG. 10 is an end elevational view of one latch needle unit of the present invention before assembly of the latches thereto;

FIG. 11 is a view similar to FIG. 4 showing the fingers formed in a metal blank used to form the latch needle unit;

FIG. 12 is a view similar to FIG. 11 showing the latch needle fingers after die-pressing the fingers to form the needle contour including the hook and the rivet hole;

FIG. 13 is a view similar to FIG. 12 after punching or stamping the metal displaced during die-pressing;

FIG. 14 is a fragmentary front elevational view of the completed latch needle unit, but prior to milling the latch house slot and insertion of the latch therein;

FIG. 15 is an end elevational view of one yarn guide unit of the present invention;

FIG. 16 is a fragmentary front elevational view of a yarn guide unit being formed showing the result of the die-pressing step to form the contour of the guides and the eye therein;

FIG. 17 is a view similar to FIG. 16 after punching or stamping the metal displaced during die-pressing; and

FIG. 18 is a fragmentary front elevational view of the completed yarn guide unit.

DESCRIPTION OF THE INVENTION

Referring to the drawings and more particularly to FIG. 1 there is disclosed a preferred embodiment of the tufting needle units of this invention fastened to a needle bar 10 of a tufting machine (not shown). A complete basic needle unit 12 is shown having a rectangular-shaped common holder, shank or support section 14 and a multiplicity of needles 16 formed unitary therewith. The unit is mounted in complementary fashion along the needle bar with a plurality of similar units, a portion of a second such unit being shown in FIG. 1. Although the number of needles selected for the unit disclosed is 12, it should be appreciated that this number depends on several factors: one being the economical production of the unit itself and another being the number of needles selected for standard replacement units. It should be appreciated, therefore, that the precise number of needles disclosed should not limit the scope of the present invention.

The shank section 14 includes a back substantially planar reference surface 18 and a top substantially planar reference surface 20, each of which is accurately machined for cooperation with the needle bar 10. The needle bar 10 includes a slot 22 which may be milled or ground therein so as to provide an accurately aligned seat for the surfaces 18 and 20 of the shank. The surfaces 18 and 20 are disclosed as lying in planes substantially normal to each other as is the slot 22, this being an effective, economical and efficient manner of providing the proper seat, but any other configuration of the surfaces and the slot that will provide accurate alignment of the needles relative to the needle bar may be used. The needle unit has a number of apertures 24 in the shank section through each of which passes a fastening screw 26 that is threaded into tapped holes (not shown) in the needle bar 10. It should now be clear that the needle units of the present invention obviate the prior art requirements of accurately boring a multiplicity of needle-receiving holes in the needle bar and of individually inserting and adjusting each needle in a bored hole. Inasmuch as precisely milled slots are simpler to produce than precisely bored holes, a greater accuracy of alignment of the needles relative to the tufting machine loopers and a more economically produced needle bar are possible with the present invention.

Each needle 16 comprises a unitary projection extending in cantilever fashion from the shank 14 of the unit. Formed in one side of the blade of each needle is a long groove 28 defined by ridges 30, which act to guide the yarn therein during needle penetration of the tufted fabric, as is well known in the art. The groove 28 extends from front surface 32 of the shank 14 and terminates at needle eye 34 adjacent to and

slightly above point 36. As is true with most present-day tufting needles, the present needles have a larger cross-sectional dimension in a direction transverse to the needle eye than in a direction parallel to the needle eye. This can be seen in FIG. 1 by cross-sectional needle 17, i.e., the fourth needle from the right. Its function is to allow the yarn groove to be a maximum, since yarn is bulky, while at the same time maintaining the needle gauge as small as desirable for a proper tufted product. The present needles, inasmuch as they can be economically produced from a relatively long flat strip of metal, as will be presently described, are twisted about their longitudinal axes so that when inserted into a tufting machine the groove 28 and the needle eye 34 will be in proper functional relationship with the looper. In the preferred embodiment the twist is 90°. The position of the looper relative to the needle instrumentalities, as shown in the aforementioned U.S. Pat. No. 3,398,708, is in a vertical plane transverse to the longitudinal axis of the needle bar. Not only does the 90° twist in the present needles position the groove 28 for proper cooperation with the looper, but since the groove extends into the front surface of the shank, the yarn, which normally comes from a spool somewhere above the needle bar, will be guided by the groove for a relatively longer distance than is the case where the yarn groove is entirely on the side of the needle opposite the looper. This allows the yarn to reach the needle eye with a minimum of unguided deviation and hence there is better control of the loop being formed. Formed on the opposite side of the needle from the yarn groove is a scarf or undercut portion 38 which, as is well known, provides clearance for the looper.

Each basic unit 12 is subdivided as by indentations or readily shearable score lines 40 and 42 into a number of subunits 44, 46 and 48. The score lines are, of course, parallel to the needles. It is to be understood that the number of subunits depends on the number of needles in the basic unit 12 and the number of needles selected for standard replacement units. A standard replacement unit 50 having four needles is shown mounted on the needle bar 10 adjacent the basic unit 12. It should be obvious that in the event of a needle breakage occurring in one of the needle subunits 44, 46 or 48 this subunit may be separated along the appropriate score line 40 or 42 or both from the remainder of the basic unit 12 and a standard replacement unit 50 substituted in its place. In the event of a needle breakage occurring in more than a single subunit either two or more standard replacement units may be inserted, or a replacement unit comprising twice or thrice etc. the number of needles of a standard replacement unit may be inserted. In the latter case the replacement units may be produced as off-the-shelf ready replacement items or may be produced from new or used basic needle units. This principle or modulus assembly allows a very quick, efficient and economical replacement of broken needles, thus reducing the machine downtime.

With reference to FIGS. 4 through 8 an economical method of producing the multineedle tufting units of the present invention will now be briefly described. A blank comprising a relatively long flat strip of metal (not shown) having a thickness equal to the desired shank thickness is inserted into a blanking die press and the strip is thereby punched to form fingers 52. The forming of the fingers 52 may also be accomplished by cutting the same from the strip. The blank, now in the condition shown in FIG. 4, is then subjected to a known die press forming or fine flow stamping operation to simultaneously contour the needles and form the scarf, the long groove and the needle eye. Of course, the scarf may be preformed in the initial metal strip if this is found more desirable. The blank, now in the condition shown in FIG. 5, is next subjected to a punching or stamping operation to remove the excess material 54 displaced during the press-forming step, the result thereof being shown in FIG. 6. The blank is now subjected to a pair of punching dies on opposite sides of the eye and the eye is rounded along both its top surface 56 and bottom surface 58 as shown in FIG. 7. The needles are then pointed on their two outer tips 60 and 62 by grinding the proper point angles. After this step, the result of which is

shown in FIG. 8, the needles are twisted preferably through 90° about their longitudinal axes so that the eyes and the yarn grooves are set into proper position for cooperation with a looper upon later fastening in a tufting machine. This twisting step coaxially aligns the eyes of all the needles and positions surfaces 64 and 66 available to a grinding operation. The final grinding of the point angles is then performed thereon. The needle unit is now ready for the reference surfaces 18 and 20 to be ground thereon and for the fastening holes 24 to be punched therein. At least one such hole must be punched in each intended subunit. Finally, the shanks of the units are sharply scored by, for example, indentations ground therein, and the units are cut to length. Of course, the proper heat treatment will then follow.

For production of needles having a smaller gauge than is practicable with the above process, the above process may be used to manufacture larger gauge units and two or more such units may then be superposed upon each other in staggered relationship so that needles of one unit are disposed between needles of the other unit or units, or two or more staggered rows of such units may be set in a needle bar having two or more milled slots.

Now referring to FIG. 9 there is disclosed the component elements of a typical latch needle used in the knitting art. Formed with the stem 70 is a hook 71 whose function is to draw the loop. Formed in the stem, as by milling, is a slot 72 in which is housed the latch 73. The latch is fulcrumed on a pivot 74 so that it may pivot by action of the yarn as is well known in the knitting art.

The latch needle unit of the present invention includes a common shank section 75 having at least a rear reference surface 76 and preferably a top reference surface 77 which are similar to the reference surfaces of the tufting needle unit, and which can cooperate with the knitting machine mounting surface. The unit, with the exception of the specific needle configuration, is in all other respects similar to the aforescribed tufting needle unit and may be manufactured and scored in like manner. FIGS. 11 through 13 show the steps of a method for manufacturing the latch needle unit beginning with a blank with fingers 78 formed therein similar to the fingers 52 shown in FIG. 4. The blank is then subjected to a die press forming or fine flow stamping operation to contour the needles and form the pivot hole 79 as shown in FIG. 12. The blank is next punched or stamped to remove the excess material 80 displaced during the press-forming step. The needles of the unit, now in the condition shown in FIG. 13, are then twisted 90° about their longitudinal axes so that they are properly oriented for later insertion into a knitting machine. This twisting step coaxially aligns the rivet holes of all the needles and positions the stem so that the latch slot may then be cut therein. The reference surfaces may now be ground thereon and fastening holes formed therein. Scoring and cutting of the units to length then follows.

Referring now to FIGS. 15 through 18 the present invention is applied, as another embodiment, to yarn guides used in the knitting operation to guide yarn to the knitting point. An eye 90 at the bulbous free end 91 of the finger element acts to guide yarn passing therethrough. The unit is similar in all respects to the needle units previously described and includes a common shank 92 having at least a rear reference surface 93 and also preferably a top reference surface 94 for mounting in a knitting machine. To manufacture the unit a blank is formed as shown in FIGS. 4 and 11, and is then die-pressed or stamped to contour the guides and form the eye. The fingerlike elements are then cleared of excess material 95 as previously described or by a similar step. The fingerlike guides are then twisted 90° about their longitudinal axes to coaxially align all the eyes, and the units are then finished in a matter similar to the above-described needle units.

It is thus clear that the present invention provides an inexpensive multielement yarn-handling device which can be quickly and accurately fastened to a yarn-utilizing machine and in which provision is made for rapidly and economically

replacing individual elements broken during the use of the device. Of course, many other embodiments of the invention may present themselves to those skilled in the art and the scope of the invention should not be limited to the described embodiments, but is to be determined from the appended claims.

Having thus set forth the nature of the invention, what I claim herein is:

1. A yarn-handling device for textile machines having a mounting surface, said yarn-handling device comprising a comblike member having a shank adapted to be fastened to said mounting surface, a multiplicity of spaced fingerlike elements extending from the shank, each of said fingerlike elements having a free end shaped to engage and control a strand of yarn, each of said fingerlike elements having a longitudinal twist between said shank and said free end.
2. A yarn-handling device as defined in claim 1 wherein said shank comprises at least a planar reference surface adapted to be accurately positioned on said mounting surface.
3. A yarn-handling device as defined in claim 1 wherein said shank includes readily shearable score lines at predetermined intervals along the surface thereof whereby said device may be subdivided at said score lines.
4. A yarn-handling device for textile machines having a mounting surface, said yarn-handling device comprising a shank member adapted to be fastened to said mounting surface, at least one fingerlike element integral with and formed of the same material as said shank, said fingerlike element having a blade portion angularly twisted about its longitudinal axis, said fingerlike element formed with a free end shaped to engage and control a strand of yarn.
5. A yarn-handling device as defined in claim 4 wherein said device comprises a multiplicity of fingerlike elements integral with said shank, each said element having a blade portion angularly twisted about its respective longitudinal axis, the free end of each element shaped to engage and control a strand of yarn.
6. A yarn-handling device as recited in claim 5 wherein each said blade portion is twisted about its respective longitudinal axis through 90°.
7. A yarn-handling device as defined in claim 5 wherein said shank comprises at least a planar reference surface adapted to be accurately positioned on said mounting surface.
8. A yarn-handling device as defined in claim 5 wherein said shank includes readily shearable score lines at predetermined intervals along the surface thereof, whereby said device may be subdivided at said score lines.
9. A yarn-handling device as defined in claim 8 wherein each said element includes an eye in the free end thereof, all of said eyes being substantially coaxial.
10. A yarn-handling device as defined in claim 8 wherein each said element includes a latch member pivotably mounted thereon.
11. A multineedle unit of a comblike configuration comprising a shank adapted for mounting in a needle bar of a tufting machine, a multiplicity of spaced needles unitary with and extending from said shank in cantilever fashion, each of said needles including a point on its free end, each of said needles being angularly twisted about its longitudinal axis between said shank and said point, means defining a longitudinal groove in each needle, and means defining an eye within each said groove adjacent said point.
12. The multineedle unit of claim 11 wherein the shank comprises at least two substantially planar abutting surfaces, said surfaces providing means for accurately positioning said unit relative to a tufting machine needle bar.
13. The multineedle unit of claim 12 wherein said shank includes readily shearable score lines at predetermined intervals along the surface thereof, each of said score lines being substantially parallel to said needles whereby said unit may be separated at said score lines into similar subunits.
14. A multineedle unit as recited in claim 11 wherein all the eyes are substantially coaxial.

15. A multineedle unit as recited in claim 14 wherein each longitudinal groove extends from said eye along the length of said needle and communicates with said shank.

16. A multineedle unit as recited in claim 12 wherein all the eyes are substantially coaxial and each of said needles includes a substantially 90° longitudinal twist such that said longitudinal groove is twisted from a first plane into a second plane at substantially 90° thereto.

17. A multineedle unit as recited in claim 16 wherein said shank includes readily shearable score lines at predetermined intervals along the surface thereof, each of said score lines being substantially parallel to said needles whereby said unit may be separated at said score lines into similar subunits.

18. A tufting needle unit having a multiplicity of needles, each of said needles comprising a shank, a point, and a blade intermediate said shank and point, each said blade having an angular twist about its longitudinal axis, said shank of each needle being common to all the needles and formed unitary therewith from a single blank, said blade having a longitudinal groove therein extending into said shank and an eye formed within each said groove adjacent said point. 20

19. A method of producing a yarn-handling instrumentality for a textile machine having a mounting surface, including the steps of forming from a blank a shank of a thickness to be secured to said mounting surface, forming a multiplicity of spaced fingerlike elements projecting from the shank, contouring each of said elements to provide a free end shaped to engage and control a strand of yarn, and twisting each element about its longitudinal axis.

20. A method as claimed in claim 19, wherein the free end of each element is shaped to provide an eye, and the elements are so twisted that the eyes are coaxial.

21. A method as claimed in claim 20, wherein each element is twisted about its longitudinal axis through 90°.

22. A method as claimed in claim 19, including the further step of forming on the shank two substantially planar abutting surfaces.

23. A method as claimed in claim 19, including the further step of scoring the surface of the shank with readily shearable score lines at predetermined intervals along said surface.
